UNITED STATES PATENT OFFICE.

NATHANIEL C. SMALL, OF AUBURN, MAINE.

TURN-SHOE.

No. 866,973.

Specification of Letters Patent.

Patented Sept. 24, 1907.

Application filed April 16, 1907. Serial No. 368,566.

To all whom it may concern:

Be it known that I, NATHANIEL C. SMALL, of Auburn, county of Androscoggin, and State of Maine, have invented certain new and useful Improvements in Turn-5 Shoes, of which the following is a specification.

My invention relates particularly to that class of shoes known in the art as turn-shoes.

Shoes of this class are popular with many people on account of the great flexibility which the soles possess, 10 but they are very liable to rip. A result which turn-shoe makers have striven to attain has been to produce a shoe that will not rip. By my invention I am able to produce a turn-shoe that will not rip and I do this without impairing the flexibility of sole. Moreover, 15 my construction leaves the greatest possible amount of wearing material in the sole and it is a construction that when worn down can be easily repaired. I do this by reinforcing the turn stitch with an adjacent substantially parallel row of stitches which pass through the 20 sole and the upper. This construction I have illustrated in the accompanying drawings, in which:—

Figure 1 is an elevation of a shoe, given for the purpose of marking the places where cross sections shown in some of the other views are taken. Figs. 2 and 3 are 25 cross sections of soles. Fig. 4 is a cross section on the line X—X of Fig. 1 as the shoe is first lasted. Fig. 5 is a cross section on the same line of my completed shoe. Fig. 6 is a view looking down on the inner side of the shoe, the section being taken on the line Y—Y of Fig. 1.

30 In making a shoe according to my method the sole 1 is fitted on its upper or flesh side with a channel 2, either with or without a shoulder as shown in Figs. 3 and 2 respectively. The bottom or grain side is fitted with a channel 4. There may be a channel flap 5 as 35 shown in Fig. 3 or simply a channel as shown in Fig. 2.

The sole is fastened to the last 6 with its grain side next to the last, by tacks 7. The upper 8 is stretched over the last and sole wrong side out and held in place by a tack 9 at the toe; or a number of tacks may be 40 used; or it may be held in any other convenient manner. The upper is then sewed to the sole by stitches T in the ordinary way. The shoe is then turned, re-

lasted and beaten out. This constitutes the turn process with the addition that I have fitted the sole with the outside channel 4. 45

The last is withdrawn and a row of stitches R is put through the sole and the upper from the channel 4 in the bottom or grain side of the sole as shown in Figs. 5 and 6. This row of stitches is close to and substantially parallel with the turn stitching T and serves to 50 reinforce and protect the turn stitch.

While I prefer the construction I have shown, with the second row of stitches outside the first, it is evident that the second row may be put either wholly inside the first or across and through the first and the same 55 advantages attained or approximated.

It will be noticed that the ordinary turn stitch, whether the upper is sewed to surface or to shoulder, lies in nearly a horizontal position and that the action of the upper from the pressure of the foot produces a 60 side strain or shearing action on the thread. By putting in the stitches R through the sole and upper there is no sawing action on them, as is the case where an inner sole is used or where the sole is split to receive the upper and the full tensile strength of the stitches R 65 comes into play to help hold the upper and sole together, reinforcing and protecting the turn stitches T, thereby making an exceedingly strong structure—one that will not rip—one that leaves the full thickness of sole for wear and which when worn can be easily repaired. 70

What I claim is:—

In a turn-shoe having the upper fastened to the sole on the flesh side in the usual manner, a row of stitches R outside of the turn stitching, adjacent to and substantially parallel therewith; said stitches passing through the said upper and the said sole, whereby the turn stitching is reinforced and protected, substantially as shown and described. 75

In testimony whereof I affix my signature in presence 80 of two witnesses.

NATHANIEL C. SMALL.
